ABSTRACT: An inspection fixture for gauging primer tubes having its sidewall formed with predetermined flash holes. The tube is rolled lengthwise as guided by a pair of longitudinally extending opposed channels formed by sidewall constructions secured to a base member. The base contains a plurality of upstanding pins at predetermined locations and which protrude above the base upper surface. The pins will be received by the flash holes of an acceptable primer tube.

PATENTED DEC 22 1970

ATTORNEYS:

INSPECTION FIXTURE

The invention described herein may be manufactured, used, and licensed by or for the Government for governmental purposes without the payment to me of any royalty thereon.

This invention relates to fixtures, and more particularly, to a fixture that facilitates inspection of primer tubes having predetermined flash holes.

It is an object of the invention to provide a test or gaging fixture by which primer tubes can rapidly be inspected and readily be accepted or rejected.

Another object of this invention is to provide such an inspection fixture that smoothly accepts satisfactory primer tubes which are rolled through the fixture.

These and other objects, features, and advantages will become more apparent from the following description and accompanying drawings in which:

FIG. 1 is a perspective view of the fixture embodying the principles of the invention.

FIG. 2 is a sectional view taken along line 2-2 of FIG. 1 with a primer tube in position for inspection.

The inspection fixture, shown generally at 10 (FIG. 1), has a base member 11 with an upper surface 12 provided with a plurality of predeterminedly located vertical apertures for selectively receiving or mounting the shaft portions of designated bulletlike pins 13. The pins 13 are of predetermined dimensions in diameter and length so as to protrude uniformly a predetermined distance above the base upper surface 12 to be readily received in the flash holes 14 (FIG. 2) of a primer tube sidewall when an acceptable or satisfactory primer tube 15 is rolled longitudinally through the fixture. During inspection operation of the fixture base 11 preferably has its rearward end elevated by means (not shown) such that the test specimens can roll forwardly down an approximate 20° incline or grade. The bullet-shaped or tapered ends of pins 13 facilitate entry and exit with the acceptable primer tube flash holes. Rejected tubes will not roll smoothly through the fixture.

Extending longitudinally along the side edges of the base member 11 and positioned laterally of the pins 13 are a pair of parallel sidewall members 16, 17 each of which is appropriately secured to the base member 11. Each sidewall or anvil 16, 17 has an overlying cap member 18, 19 of relatively less height but greater width than its corresponding sidewall 16, 17. Each

cap member 18, 19 is appropriately secured to and extends along its sidewall member 16, 17 and each cap extends inwardly of its sidewall member 16, 17 and each cap extends inwardly of its sidewall to provide lengthwise extending, opposed channels that receive end portions of a rolling primer tube. The height of side members 16, 17 preferably is slightly greater than the outside diameter of the primer tube being inspected.

Mounted or appropriately secured in longitudinally extending grooves 20, 21 provided in the base upper surface 12 are flexible rubber strips 22, 23. The properly secured flexible strips 22, 23 protrude above the base upper surface a slight distance, but less than that of the protruding pins 13, and run longitudinally between predetermined groups of upstanding pins 13.

The purpose of the flexible friction strips 22, 23 is to assure that the primer tube will roll with a minimum of slippage.

I wish it to be understood that I do not desire to be limited to the exact details of construction shown and described, for obvious modifications will occur to a person skilled in the art.

I claim:

1. An inspection fixture for gaging primer tubes having predetermined flash holes in the sidewall thereof, comprising: a base member having an upper surface; a plurality of bulletlike pins upstanding in said base member at predetermined locations thereon and having upper end portions protruding above said base upper surface; a pair of longitudinally extending parallel sidewalls positioned laterally of said pins; and means on said sidewalls defining lengthwise extending opposed channels for receiving end portions of a rolling primer tube; and so constructed and arranged that anyone of said pins will preclude forward rolling of said primer tube unless it contains the appropriate flash holes in its sidewalls.
2. The structure of claim 1 wherein said base upper surface has a plurality of longitudinally extending flexible strips protruding above said base upper surface a distance less than said protruding pins.
3. The structure of claim 3 in which said channel defining means includes a pair of longitudinal cap members overlying corresponding ones of said parallel sidewalls and extending inwardly therefrom.
